LOCK

Original Filed Nov. 18, 1927

INVENTOR

George A. Long,
by
Arthur B. Jenkins

ATTORNEY.

UNITED STATES PATENT OFFICE

GEORGE A. LONG, OF HARTFORD, CONNECTICUT, ASSIGNOR TO THE LONG SECURITY LOCK COMPANY, OF HARTFORD, CONNECTICUT, A CORPORATION OF CONNECTICUT

LOCK

Original application filed November 18, 1927, Serial No. 234,258. Divided and this application filed May 16, 1930. Serial No. 452,938.

My invention relates to that class of devices which are employed for securing doors and similar closures, and an object of my invention, among others, is the provision of means for simplifying the act of operating a lock for such closures.

One form of device embodying my invention and in the construction and use of which the objects herein set out, as well as others, 10 may be attained, is illustrated in the accompanying drawing, in which—

Figure 1 is a face view of my improved key.

Figure 2 is an end view of the same.

Figure 3 is a face view showing one of the 15 key members partially removed from the other member and completely removed from a lock, a portion of which is shown in section.

Figure 4 is an isometric view showing the two key members substantially separated.

20 Figure 5 is a face view of a lock used in connection with my improved key.

Figure 6 is an edge view of the same.

Figure 7 is a view in section on a plane denoted by the dotted line 7—7 of Figure 9.

25 Figure 8 is a view similar to Figure 7 but with the locking bolt in its unlocked position.

Figure 9 is a view in section on a plane denoted by the dotted line 9—9 of Figure 7.

Many locks in use at the present time embody mechanisms requiring the use of two 30 keys for the operation thereof to gain access to the compartment closed by the door or other closure to which the lock is affixed. Such instances are common in safe deposit

35 boxes or similar compartments in banks or other places wherein a key possessed by the custodian or guard of the box is required to effect a portion of the unlocking operation, and the key of the person renting the box is

40 required to complete the operation to release the locking element. In this operation the key of the custodian must be first inserted, the operation partially performed thereby, the custodian's key then removed to permit

45 insertion of the key of the person renting the box, whereupon the operation of unlocking the bolt is completed by the last mentioned key.

This application is a division of my copending application Serial Number 234,258, filed

November 18, 1927 on which issued my Patent No. 1,765,280, dated June 17, 1930, the claims of this present application having been formerly embodied in the application of said patent.

55 By the use of my improved key, illustrated and described herein, the operation hereinbefore mentioned is greatly simplified in that only one operation is required to effect opening movement of the lock mechanism and necessitating one insertion only of the key. My improved lock mechanism embodies a single opening only for the key, such key, however, comprising a plurality of separable members, two of such members being employed in that development of the invention illustrated and described herein, wherein, in the drawing, the numeral 10 indicates a lock case for containing the locking mechanism, such mechanism, generally speaking, comprising at least two sets of tumblers. The tumblers in the various sets may be of different types, and said sets may be variously arranged, the mechanism herein illustrated very satisfactorily answering the purpose 60 and embodying a set 11 of pin tumblers placed in a well known manner in connection with a barrel or key center 12 rotatably mounted in the case, and a set of flat or leaf tumblers 65 13 pivotally mounted in the case. The pin tumblers are operated by the key to release or secure the barrel or key center and the flat or leaf tumblers operate to release or secure the locking bolt in a manner that will 70 be readily understood.

80 My improved key is composed preferably of two members 14—15 divided lengthwise and having means for removable insertion of such members within the key center or barrel that is rotated to operate a locking bolt 16. In the structure herein shown the key member 14 is bitted or notched to receive the pin tumblers, and the member 15 is provided with angularly shaped bits or notches properly 85 arranged to operate the leaf or flat tumblers. When the key has been operated to partially rotate the barrel the member 14 may be removed, the member 15 being retained in the barrel and, in fact, being secured therein 90 95 100

against removal when the locking bolt 16 is thrown back.

Each of the members 14 and 15 has a retaining notch 17 to receive a lip 18 extending around the central opening in an escutcheon 19, in which opening the outer end of the key center or barrel 12 is located. Entering notches 20 are formed in the lip 18, as shown in Fig. 5, and a key releasing notch 21 is also formed in said lip.

In order that the two members of the key may be securely, temporarily held together one of said members, as the member 15, has a sloping shoulder 22 that the end of the section 14 is fitted to. A thumb piece 23 of the section 14 has an elongated lug or rib 24 that is received in a slot 25 in a thumb piece 26 of the key member 15. A bridge 27 closes the ends of the slot 25 and is arched, as shown in Fig. 4, thereby forming a groove 28 to permit passage of the lug 24 underneath the bridge.

In the operation of the key in connection with the lock mechanism, for instance as that of a safe deposit box, the custodian or guard takes the separable key member 15 from the possessor of the box and attaches it to the separable key member 14 in the custody of said guard, and as shown in Fig. 1. The assembled key is then inserted in the lock having the parts in the position shown in Fig. 7 of the drawing. The key member 14 will place the pin tumblers 11 with their ends all flush with the mouths of their respective openings, thus enabling the barrel or key center 12 to be rotated. The key now being turned in a clockwise direction to the position shown in Fig. 8, wherein the shoulder on one side of the notch 17 will be located opposite the releasing notch 21, the key member 14 may be removed by sliding it relatively with respect to the key member 15, and as illustrated in Fig. 4. The member 15 of the box owner, however, cannot be removed when in this position for the reason that the inner shoulder of its notch 17 is against the inner surface of the lip 18.

The operation above described, however, has unlocked the door, the parts of the lock being in the position shown in Fig. 8, and said door may be opened. When the door is again closed, all that is required to lock it is to turn the key member 15 that has been retained in the lock in a contra-clockwise direction, or to the left, when the locking members will be returned to the position shown in Fig. 7, and the box door will be locked. The key member 15 may now be readily removed from the lock.

It will thus be seen that in place of two keys I have produced a single key composed of two members, and the complete key is operated in the same manner as a single key, but at the end of the unlocking operation with respect to the key center or barrel one member of the key may be removed, leaving

the other member to be made use of in continuing the unlocking operation.

It should here be noted that the location of the notch 21 governs the position of the key when the section 14 may be removed, and while, in the structure shown, this is at a point where a stop is provided at the completion of the unlocking operation, such notch may be located to permit removal of the section 14 at any time after the barrel 12 has been turned from its normal locking position.

It may further be noted that the blades of the two key members are located in the same plane by offsetting one or both of said blades from the plane of its thumb piece. In the structure herein shown the blade of the key member 15 is entirely offset from the plane of its thumb piece into the plane of the thumb piece of the key member 14.

It is here briefly stated that the lock shown is of that type wherein the tumblers 13 have notches adapted to register with detents 29 to permit the locking bolt to be drawn back, the tumblers of that part of the set 11 not located in the barrel 12 being located in the tumbler block 30. The barrel 12 has an arm 31 to enter a notch in the side of the locking bolt for the purpose of moving said bolt when permitted by the tumblers 13 which are properly located for that purpose by the bits on the key member 15.

This application is a division of my co-pending application S. No. 234,258, filed November 18, 1927, and is for the purpose of covering a portion of the invention divided out of said co-pending application.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A lock including a key receiving controller member, locking elements therefor, a bolt and locking elements therefor, said parts being adapted to be operated by a two-part key having one part operable to release said controller member locking elements for movement of the controller to its advanced position and the other operable to release said locking bolt locking elements, said lock also including means to permit removal of one of said key parts with the controller member in its advanced position after it has been moved from its key entrance position.

2. A lock including a key receiving controller member, locking elements therefor, a bolt and locking elements therefor, said parts being adapted to be operated by a separable

two-part key having oppositely disposed working edges, one part comprising one of said edges being operable to release said controller member locking elements and the 5 other part comprising the other working edge being operable to release said locking bolt locking elements, said lock also including means to permit removal of one of said key parts with the controller member in its advanced position after it has been moved from 10 its key entrance position.

GEORGE A. LONG.
